UNITED STATES PATENT OFFICE

2,662,391

METHOD OF CONSTRUCTING BUILDINGS

William P. Neil, Pasadena, Calif.

Application October 15, 1949, Serial No. 121,622

2 Claims. (Cl. 72—1)

1

My invention relates to a method of constructing concrete or similar buildings.

One of the principal objects of this invention is to devise a new, novelly efficient, and economical method of constructing or fabricating a concrete or similar building, principally from preformed or precast building elements, and particularly from elements made of concrete, or the like.

An important feature and step in my method consists in the construction of a wall by simply, effectively, rigidly, and economically securing together, by a grout, the adjacent lateral edges of separate preformed or precast wall slabs, and particularly in securing together, in the described manner, longitudinally grooved half-columns cast at the lateral edges of the slabs.

An important object also of this invention is the economical provision on the building site of a novel method for molding or casting of concrete, or the like, wall slab elements which may be readily raised and moved into position, or aligned with other similar elements, for constructing a wall, a more specific object being the provision of a method of molding or casting such slab elements upon the surface of a previously cast and set floor of the building.

Another important object of this invention is the provision of a novel method of constructing a building, which consists in the placing and grouting of separate wall slab elements on and to a suitable footing, and casting a concrete floor, for the building, with the edges of the floor against, joined to, and reinforced with the wall slabs a considerable distance above the footing or bottom ends of the slabs.

A further important object of this invention is the provision of a novel method of tying together the upper portions of adjacent wall slabs and simultaneously tying the wall slabs at one side of the building with corresponding ones at the opposite side thereof.

With these and other objects in view, as will appear hereinafter, I have devised a method of constructing concrete or similar buildings, and one having novel single and combination of steps in the effecting of the construction, as will be hereinafter described in detail, and particularly set forth in the appended claims, reference being had to the accompanying drawings which illustrate the application or practice of the method.

In the drawings:

Fig. 1 is a fragmentary perspective view of a building incorporating an arrangement of elements designed to be erected in accordance with

2

my method of construction, certain elements, and portions of others, being broken away and shown in section to facilitate the illustration;

Fig. 2 is an enlarged fragmentary, sectional elevation showing, in a preferred form, a footing, a portion of a wall element supported thereon, and a portion of the floor of the building joined to the wall element;

Fig. 3 is an enlarged sectional view thereof in plan, taken through 3—3 of Fig. 1; and;

Fig. 4 is a small scale view in plan, showing the method of molding or casting the wall slab elements on the previously cast and set floor of the building.

15 The building illustrated in Figs. 1 and 2 consists essentially of a footing 1, separate precast wall slabs 2, a middle floor slab 3, a joining floor slab element 4, a tie beam 5, and floor or roof elements 6.

20 The footing 1 may be prefabricated or precast and placed on the ground in the desired position or location at which the building is to be erected. As shown, it is located or sunk considerably below the surface or top level of the ground, designated

25 G. But the footing is preferably, and is designed to be, cast in place in a prepared furrow G', as shown. It may be made in short lengths, but is preferably continuous, as shown. The top is flat and has a relatively wide, longitudinally extending slot or depression 1a.

30 The wall of the building is made of precast wall units or wall slabs 2, and these are supported with their bottom edges on the footing 1 with the lateral edges of each slab juxtaposed to the lateral edge of the next adjacent slab.

35 The wall slabs shown comprise slab portions or members 2a at the lateral edge portions of which are provided integrally cast pilasters or column portions 2b.

40 The wall portion 2a of each slab element is preferably supported on the top face of the footing while the bottom end of the column portion overhangs the slot or depression 1a. The slab element is secured in position by placing the bottom end of the column portion on a grout bed 7 provided within the depression 1a, the depression being preferably filled with the grout.

45 The adjacent slab elements are also secured and interlocked with each other by grout 8, as shown in Fig. 3.

The slab elements are fabricated or cast on the building site. They are, according to my invention, molded or cast on the previously fabricated and set concrete floor 3 which is laid on 55 the surface of the group G, considerably above

the footing 1, and with the edges 3^a spaced considerably from the wall or building line.

If necessary the edge of the floor may have a groove or projection, or reinforcing (not shown) extending therefrom. In this floor are also cast anchor studs 9, or inserts for such studs, for the purpose hereinafter described.

On the surface of the floor 3 are laid forms 12 in which the slabs are separately cast. When set, the slabs are raised, by first raising the normally upper portion. They are then transported and placed or arranged on the footing 1, as described above.

During the placing of the wall slabs 2 on the footing, and the setting of the grout 7 at the bottom ends thereof, the slabs are temporarily held in vertical or other desired position by one or more adjustable braces 10, which are secured at their opposite ends to the studs 9 and similar studs 11 anchored within the slabs, as shown in Fig. 1.

After the wall slabs 2 are erected, as described, the space between the edge of the previously poured floor 3 and the inner side of the wall is filled with earth or other filler F and topped with the aforementioned floor section or slab element 4, thereby rigidly joining the floor slab 3 with the wall slabs 2.

As shown in Figs. 1 and 2, there are provided suitable reinforcing rods 13, one end of each being anchored within the slabs during the fabrication of the latter.

After the walls are erected, as described, the pilasters or half-columns of adjacent slabs are further tied together by other means, which is here shown as the aforementioned beam or girder 5. The latter element, or a continuation of several, also ties together the opposite walls of the building. It may be either cast in place or pre-cast. In the end portion of beam 5 is anchored a plate 14, which is welded to a plate 15 which may be anchored within the upper end of each column portion 2^b. As shown, anchor studs 16 are provided in each of the column portions, and the plate 15 is secured to the ends of the column portions by the studs 16, thereby additionally tying together the slabs at their upper portions. Thus, adjacent slabs are secured together by the plate 15 and the beam 5, and the opposite walls are stabilized with respect to each other by the beam 5 or a series of them.

The slabs 6, which may be floor or roof elements, may be supported on the beam or beams 5 and on the upper portions of the wall comprising the slabs 2.

Though I have disclosed and described a particular method of constructing a concrete or similar building, or portions of a structure, and have

described specific steps in carrying out my method, I do not wish to be limited to the same, but desire to include in the scope of my invention the method and steps substantially as set forth in the appended claims.

I claim:

1. A method of constructing a concrete wall and floor supported on the ground comprising laying a footing in a trench with the upper surface of the footing below the surface of the ground, casting a concrete floor on the surface of the ground adjacent to and spaced from the footing, casting concrete wall panels on the cast floor and allowing the panels to set, raising the wall panels and setting them in an upstanding position on the footing, applying grout on the footing and against the wall panels for joining the wall panels and the footing, bracing the wall panels in position, filling the space between the panels and the sides of the footing trench and casting a concrete floor section on the trench fill from the concrete floor to the panels.

2. A method of constructing a concrete wall and floor supported on the ground comprising laying a footing with a grooved upper surface in a trench with the upper surface of the footing below the surface of the ground, casting a concrete floor on the ground adjacent to and spaced from the footing, casting concrete wall panels on the cast floor and allowing the panels to set, raising the wall panels and setting them in an upstanding position outwardly of the groove of the footings and on the footings, applying grout into the groove and against the wall panel for joining the wall panels and the footing, bracing the wall panels in position, filling this space between the panels and the sides of the footing trench, and casting a concrete floor section on the trench fill from the concrete floor to the panels.

WILLIAM P. NEIL.
